US0D1038108S

(12) **United States Design Patent** (10) **Patent No.:** **US D1,038,108 S**
(45) **Date of Patent:** **** Aug. 6, 2024**

(54) **FOLDABLE PHONE HOLDER**

(71) Applicant: **Dongguan Juyuan Precision Technology Co., Ltd.**, Dongguan (CN)
(72) Inventor: **Zhihu Xie**, Dongguan (CN)
(73) Assignee: **Dongguan Juyuan Precision Technology Co., Ltd.**, Dongguan (CN)

(**) Term: **15 Years**

(21) Appl. No.: **29/916,871**

(22) Filed: **Nov. 16, 2023**

(30) **Foreign Application Priority Data**

Assistant Examiner — Rodolfo Castro, Jr.

(57) **CLAIM**

The ornamental design for a foldable phone holder, as shown and described.

DESCRIPTION

FIG. 1 is a front perspective view of a foldable phone holder showing my new design in a first configuration;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the foldable phone holder of FIG. 1 shown in a second configuration; and, FIG. 9 is a front perspective view of the foldable phone holder of FIG. 1 shown in a third configuration.

1 Claim, 9 Drawing Sheets
